HOLDER FOR BRUSHES OR THE LIKE

Joseph Abadessa, Jr., Rutherford, Frank Abadessa, Glen Rock, and William L. Burgess, Hasbrouck, N. J.

Application April 27, 1954, Serial No. 30,198

Term of patent 3½ years

(Cl. D9—3)

FIG. 1

FIG. 3

Fig. 1 is a front elevational view of a holder for brushes showing my new design;

Fig. 2 is a top plan view; and

Fig. 3 is an end elevational view thereof looking toward the right of Fig. 2.

I claim:

The ornamental design for a holder for brushes or the like, as shown.
